UNITED STATES PATENT OFFICE.

GEORGE FRANCIS PITTA, OF WIMBLEDON, ENGLAND.

GOLF-CLUB.

1,235,922.

Specification of Letters Patent.

Patented Aug. 7, 1917.

Application filed February 15, 1915. Serial No. 3,287.

To all whom it may concern:

Be it known that I, GEORGE FRANCIS PITTA, a subject of the King of England, residing at Wimbledon, Surrey, England, 5 have invented certain new and useful Improvements in Golf-Clubs, of which the following is a specification.

This invention relates to golf clubs provided with heads made wholly or partly of metal and in such a manner that the blade, 10 or part striking the ball, is separate from the shaft socket, and adapted to be turned and retained in various angular positions.

In a club of this description it is desirable 15 to have thorough rigidity, combined with ready adjustability for swiveling the blade to any degree of angle, to suit the requirements of play for various strokes, so as to serve, with one club, the purposes of several 20 clubs as usually made, such as those known as, "putters", "mashies", "lofters", "cleeks", "drivers", "jiggers", "niblicks", "spoons", and the like; and for left-hand play in emergencies.

25 In constructing a golf club according to my present invention, I provide the end socket with an eye, which eye is furnished at one side with a spherically hollowed-out portion, which is roughened or knurled, and 30 on the other side with a spherically projecting portion, which is also roughened or knurled. This eye is circular where it opens into the spherically hollowed-out portion thereof, but is prolonged on the other side 35 into a tapering elliptical or oval slot, the longer axis of the ellipse or oval being in a plane passing through the axis of the shaft. The blade is provided with a spherical heel portion corresponding with the hollowed-out 40 portion in the eye, and roughened or knurled.

A screw-threaded stem is furnished to the blade, adapted to pass through the eye, and a washer or its equivalent is provided having a hollow spherical portion adapted to fit 45 over the spherically projecting portion around the eye and having a flat portion at the outside. A nut is further provided, adapted to screw on the end of the screw-threaded stem and to lock the blade in position after adjustment.

50 With this joint, which resembles a partial ball and socket joint, the blade can be turned about its center line or axis, and may 55 be adjusted, to a considerable extent, with relation to the axis of the shaft, thus ena-

bling a suitable adjustment to be made for the different angles of the blade to the shaft, in "drivers" as compared with "irons," "putters," and the like.

60 And in order that my said invention may be clearly understood, I will now proceed to describe the same with reference to the drawing accompanying this specification, which shows a club constructed according to 65 my said invention.

Fig. 1 is a side elevation, showing the blade in position.

Fig. 2 is a back view with the blade removed illustrating the construction of the 70 socket eye.

A is the end socket, which is provided with an eye comprising a spherically hollowed-out portion A¹, the surface of which is roughened, a circular aperture A² and a 75 tapering elliptical or slotted portion A³ the longer axis of the ellipse being in the plane passing through the axis of the shaft. The portion A⁴ at the back of the eye is of convex spherical form, and is roughened or 80 knurled.

B is the blade, which is provided with a spherical heel, corresponding with the spherical surface A¹ in the eye, and which is roughened, a screw-threaded stem B¹ 85 adapted to pass through the eye and to rotate therein and to be set at various inclinations with respect to the axis of the shaft, the pin B¹ moving in the elliptical slot. D is a washer having a hollow spherical portion 90 adapted to fit over the spherical part A⁴ on the eye, and a flattened portion at the back, and C is a nut.

95 With this construction, as will be perfectly obvious, it is simply necessary, in order to adjust the blade with respect to the axis of the shaft, or to turn the blade, to loosen the nut C, bring the blade in the required position, when, on tightening up the nut, it will be held perfectly secure.

100 The nut C and washer D are shown at Fig. 1 in the mid-position in full lines, the extreme positions being indicated in dotted lines.

Any turning moment on the blade simply 105 tends to tighten the nut and does not cause the parts to work loose.

What I claim and desire to secure by Letters Patent in the United States of America is:—

110 In a golf club, the combination of an end socket provided with an eye, the said eye

comprising a spherically hollowed-out roughened portion having a circular hole at the bottom and an elliptical slot tapering outward from the said hole, the major axis 5 of the ellipse being in the same plane as that containing the axis of the socket, a spherically convex roughened portion surrounding the elliptical opening of the slot: a blade having a spherical heel portion with a 10 roughened surface, such spherical heel portion corresponding to the spherically hollowed-out portion of the eye, a screw-threaded stem to the said blade adapted to pass through the hole and the elliptical slot,

a washer provided with a hollow spherical 15 portion adapted to fit over the spherical projecting portion around the elliptical slot and having a flat portion at the outside, and a nut adapted to screw on to the end of the screw-threaded stem, all substantially as and 20 for the purposes set forth.

In testimony whereof I affix my signature in presence of two witnesses.

GEORGE FRANCIS PITTAR.
